UNITED STATES PATENT OFFICE.

JAMES H. WAGENHORST, OF AKRON, OHIO.

METAL WHEEL.

Application filed December 5, 1918. Serial No. 265,403.

To all whom it may concern:

Be it known that I, JAMES H. WAGENHORST, a citizen of the United States, residing at Akron, in the county of Summit and State of Ohio, have invented a certain new and useful Improvement in Metal Wheels, of which the following is a full, clear, and exact description, reference being had to the accompanying drawings.

10 This invention relates generally to metal wheels, and more particularly to one comprising a hub, a felly intended to receive a demountable tire carrying rim, and a plurality of flat or stripped metal spokes rigidly 15 fastened to the hub and tensioned as their outer ends are connected to the felly.

One object of the invention is to provide a cheap, simple, and durable wheel, one which can be quickly and easily assembled, and one 20 in which the wheel adjustment or the bringing of the wheel body into proper alignment can be accomplished by and with the tensioning of the spokes, and another advantage of a construction of this character is, that 25 by means of strip spokes all circumferential torque is cared for and by giving the proper spread to the spokes at their inner ends a wheel can be provided capable of standing lateral strains from either direction.

30 Another object of the invention is to construct the spoke ends so as to permit optional tensioning and at the same time provide a rigid connection between the spoke and felly.

35 Another object is to provide for the proper tensioning of each individual spoke irrespective of its angle with reference to the axis of the wheel, and it is also an object of the invention to provide for a simple and economical manufacture of the spokes.

40 With these several objects in view and certain others which will become apparent, the invention consists in the novel features of construction and combination hereinafter 45 fully described and set forth in the appended claims.

In the drawings forming a part of this specification, Fig. 1 is a side elevation, partly in section, of a wheel body embodying one 50 form of my invention; Fig. 2 is a transverse vertical section through the hub and rim; Fig. 3 is a detail sectional view showing a slight modification of the felly; Fig. 4 is a plan view of the blank from which the 55 spokes are cut; Fig. 5 is a side elevation partly in section of a wheel in which the in-

ner and outer spokes are arranged alternately; Fig. 6 is a detail perspective view of one of the spokes; Fig. 7 is a detail view partly in section showing on a somewhat larger scale the connection between the spoke end and felly; Fig. 8 is a transverse sectional view showing another form or method of connecting the inner ends of the spokes; Fig. 9 is a detail perspective view of one end of one construction of hub used in connection with this type of wheel; Fig. 10 is a sectional view showing a slightly different manner of connecting the outer end of the spokes to the felly and also the manner of connecting the 60 brake drum and spoke ends and hub; Fig. 11 is a detail perspective view of the spoke ends shown in Fig. 10; Fig. 12 is a detail sectional view showing a slightly modified construction of hub; and Fig. 12^a a view, 70 similar to Fig. 11, showing a modification of the outer spoke-end construction.

In the practical embodiment of my invention I employ a metallic hub A having an exterior annular flange B adjacent its inner end and a similar flange C adjacent its outer end and these flanges are formed with a bead or rib B' upon their respective inner and outer faces and these beads or ribs can be in the form of a circle or they may be 75 polygonal in form, the number of sides being determined by the number of spokes used in connection with the wheel. The felly or fixed rim D is of sheet metal and is intended to receive a demountable tire carrying rim 80 and may be of any desired type or construction, and in Fig. 2 I have shown this felly as having a flat base on bottom portion while in Fig. 3 the base is inclined as shown at D' and D^a for the purpose hereinafter explained.

The spokes E are of strip or sheet metal, tapered slightly at their inner ends as shown at E' in order that they may be assembled about the hub, and at their outer ends each spoke is formed with a shank or spindle portion E^a which is adapted to be projected through an opening F produced in the base or bottom of the metallic felly or fixed rim and the end of this spindle or shank portion E^a is threaded as shown at E^b in order to receive the tensioning or fastening nut G. In punching the holes F a portion of the metal is carried outwardly as shown at F' in Fig. 7 providing a reinforcement at this point and also a rounded edge into which can be drawn the filleted portion F^a of the 105 110

spoke end it being preferable to form this fillet at the juncture of the flat portion of spoke with the shank or spindle portion thereof.

- 5 In practice I propose to run the spokes out in a continuous strip as illustrated in Fig. 4, the inner end portions of adjacent strips being united and the shank or spindle portion also united and the continuous strip or 10 blank comprising a series of spokes can be divided at the proper points to provide the separate and individual spokes. The shaping of the spokes with the taper at the inner end can be accomplished at the same 15 time that the spokes are divided at this point. By this method of making the spokes I obtain greater economy in their manufacture and at the same time maintain great uniformity in the spokes.
- 20 The inner end of each spoke is also preferably formed with a corrugation H which enables the spoke to be fitted against the rib or beaded hub flange and the inner and outer hub rings I and K are provided with 25 grooves I' and K' into which the corrugations H are adapted to fit when said rings are placed upon the hub and fastened to the hub flanges by means of bolts L which pass through the rings and flanges and the spoke 30 ends at the points where they are corrugated. By this means the inner ends of the spokes are securely connected to the hub and all possibility of movement at this point of attachment is eliminated. In Figs. 1 and 2 35 I have shown the inner and outer spokes in alignment whereas in Fig. 5 the inner and outer spokes are arranged alternately.
- Instead of a bead from the hub flange a 40 protuberance could be provided and corresponding recesses produced in the rings I and K and the bolt openings in the spoke could be flanged by drawing a portion of the metal through at the time the bolt openings are punched and this flanged portion 45 would receive the protuberance on the hub flange and would in its turn fit into the recess in the flange ring.
- The outer ends of the spokes are first projected through the openings in the felly and 50 the nuts placed thereon to maintain them in their proper position and then by tightening up the nuts the spokes are placed under tension and the adjustment or trueing of the wheel accomplished and it will be noticed 55 that each and every spoke can be given the proper tension irrespective of its angle with reference to the axis of the wheel and furthermore by rounding the openings in the felly and filleting the spoke end a rigid connection will be obtained which at the same 60 time lends itself to the optional tensioning of the spoke it being understood that a very slight longitudinal or stretching movement will place the entire spoke under 65 proper tension and by connecting the inner

and outer ends of the spoke to the hub and felly respectively all tendency towards circumferential movement is completely avoided.

It will be noted that the outer series of 70 spokes are given a greater inclination than the inner series and in order to provide the proper bearing supports for these differently inclined spokes I provide beveled spacing washers L' beneath the nuts and bearing 75 upon the face of the felly, or the base of the felly can be given the proper angles of inclination as shown at D' and D² in Fig. 3.

By having the spokes separate each spoke 80 can be properly tensioned irrespective of its inclination, and another advantage of separate spokes is that in case one spoke should become bent or broken it can be quickly 85 and easily removed and a new one substituted and properly tensioned without disturbing the remaining spokes. In Figs. 1, 2, and 3 and likewise 8 and 12 I have shown the outer ends of the spokes attached to the felly at different points that is, the inner 90 series attached adjacent to the inner side of the felly and the outer series attached to the outer side of the felly, except in Fig. 8 where the spokes cross each other and the reverse order is obtained. In Fig. 10 how- 95 ever I have shown the spoke ends brought together and projected through a single opening in the felly and a common nut applied to the ends which when combined 100 constitute a cylindrical shank or spindle to receive the nut. The spoke ends for this construction are illustrated in detail in Fig. 11.

In Figs. 8, 9, and 12 I have shown another 105 method of connecting the inner ends of the spokes to the hub which consists in providing hub flanges M, the inner and outer faces of which are inclined corresponding with the inclination it is desired to give 110 to the spoke. The inner end of each spoke is bent backwardly and inwardly upon itself as shown at N and this bent or hooked end is brought into engagement with a ring O, frusto-conical in form, the 115 inclination of its faces corresponding with the inclination of the hub flanges M and the inclination of the spokes. The hooked ends of the spokes are brought into engagement with the rings and then the outer ends of 120 said spokes projected through the felly and the spokes tensioned, and it is obvious that as these spokes are all brought under proper tension the rings with the spokes connected thereto will be brought into engagement 125 with the hub flanges which arrest their movement and thereby maintain the inner ends of the spokes in a thoroughly rigid position. If desired the rings could be made with shallow radial depressions to receive 130 the spoke ends and the hub flanges M could

also be made with shallow radial depressions M' either to receive the spoke ends in case they project beyond the face of the ring or these depressions could receive projections formed upon the rings if desirable, the idea being that by having mating radial projections and depressions upon the hub flanges and rings all possibility of circumferential movement at these points will be avoided.

In Fig. 10 I have shown the inner end of the inner spoke as turned in the reverse direction as shown at M' in order to be brought into engagement with the inclined portion P' of the brake drum P , and bolts P^2 can be passed through the hub flange, brake drum, and if desired through the spoke ends. Where a limited number of spokes are employed the hub flanges M^2 can be formed with undercut grooves M^3 as most clearly shown in Fig. 12, and into which the hooked ends of the spokes can be brought into engagement and in certain instances it may be desirable to have spaced radial projections instead of a continuous hub flange in order that the hooked end of the spoke may be inserted laterally. By connecting the inner ends of the spokes through the employment of the ring in connection with the return bend of the spoke end it will be seen that a very cheap and easily assembled wheel is provided completely eliminating the use of bolts for effecting the connection between the spoke ends and hub, and it is obvious that when all of the spokes are properly tensioned the central connecting ring will be held absolutely fixed in its proper position.

This form of connection could also be used with a straight hub flange and flat ring, that is flange and ring perpendicular to the axis of the wheel, instead of having the hub flange and ring upon an inclination.

It will thus be seen that I provide several novel forms of metal wheel all of which embody the same general features of construction and advantage, namely the individual and optional tensioning of strip metal spokes whereby wheel adjustment is accomplished and circumferential torque avoided and at the same time a wheel provided capable of withstanding lateral strains and maintaining loads without affecting any of the connections between the several parts of the wheel body.

Subject matter disclosed but not claimed in this application is claimed in a divisional application Serial No. 668,534 filed Oct. 15th, 1923.

Having thus described my invention, what I claim is:

1. A metal wheel comprising a hub, a plurality of strip spokes connected at their inner ends to the hub and terminating at their outer ends in shanks or spindles and a felly

having openings through which the shanks or spindles project and fastening means applied to said shanks or spindles for connecting the spokes with the felly and simultaneously tensioning said spokes.

2. A metal wheel comprising a hub, a plurality of strip metal spokes having their inner ends connected to the hub and held against circumferential movement, the outer ends of said strip spokes terminating in spindles, and a sheet metal felly having openings through which the spindles are projected and nuts screwed upon said spindles to secure the outer end of the spokes to the felly and simultaneously tension said spokes.

3. In a metal wheel, the combination with a hub, strip metal spokes terminating in spindles the juncture of the strip and spindle being filleted and a sheet metal felly having apertures therein to receive the spindle and filleted ends of the spoke the edges of said apertures being rounded, and fastening means applied to the ends of the spokes whereby said spokes are connected to the felly and radially tensioned.

4. A metal wheel comprising a hub having flanges and a sheet metal felly having apertures, and a plurality of strip metal spokes the inner ends of said spokes being shaped for engagement with the hub flanges and means for holding said ends in engagement, the outer ends of said spokes being threaded and projected through the apertured felly and nuts secured upon said threaded ends for fastening and tensioning the spokes.

5. A metal wheel comprising a hub having radial flanges, a sheet metal fixed rim, an outer series of strip sheet metal spokes having spindles at their outer ends, said outer series of spokes being connected at their inner ends to the outer hub flange, the outer ends of said spokes passing through the sheet metal fixed rim and connected thereto, an inner series of strip sheet metal spokes having spindles at their outer ends, said outer ends passing through the sheet metal fixed rim and connected thereto, the inner ends of said inner series of spokes being connected to the inner hub flange, the angle of inclination of the outer series of spokes to the axis of the wheel being different from the angle of inclination of the inner series of spokes.

6. A metal wheel comprising a hub and a sheet metal felly, and a plurality of strip metal spokes connected at their outer ends to the felly, the inner ends of said spokes being bent back upon themselves and an annulus to which said inner ends of the spokes are connected, said spokes being tensioned whereby the annulus is held in engagement with the hub.

7. A metal wheel comprising a hub having

flanges, a felly having apertures and a plurality of strip metal spokes, the inner ends of said spokes being bent back upon themselves, the outer ends of said spokes being 5 threaded and projected through the felly, nuts applied to the threaded ends of said spokes whereby said spokes and felly are connected together and the spokes tensioned, and an annulus to which the inner ends 10 of the spokes are hooked, the spokes being arranged obliquely with reference to the plane of the wheel, the annulus and spokes being held in locked relation with the hub.

8. A metal wheel, a hub, a felly, a plurality of strip spokes having their inner 15 ends bent back upon themselves, the outer ends of said spokes being connected to the felly and tensioned, and a brake drum, the

inner ends of said spokes being connected to the inner portions of said brake drum, and 20 means for connecting said brake drum to said hub.

9. A metal wheel comprising a hub having flanges, said flanges having projections, a sheet metal felly, and a plurality of strip 25 metal spokes, the inner ends of said spokes being shaped for engagement with the hub flanges and the projections thereon, and means for holding said ends in engagement with said hub flanges, the outer ends of said 30 spokes being connected to the sheet metal felly.

In testimony whereof, I hereunto affix my signature.

JAMES H. WAGENHORST.
